UNITED STATES PATENT OFFICE.

RICHARD T. CLARKE, OF COLUMBUS, OHIO.

DESIGN FOR A BUTTON-ENGAGING ATTACHMENT FOR SHIRT-WAISTS.

SPECIFICATION forming part of Design No. 35,705, dated February 11, 1902.

Application filed November 29, 1901. Serial No. 84,141. Term of patent 7 years.

To all whom it may concern:

Be it known that I, RICHARD T. CLARKE, a citizen of the United States, residing at Columbus, in the county of Franklin and State of Ohio, have invented and produced a new and original Design for Button-Engaging Attachments for Shirt-Waists, of which the following is a specification, reference being had to the accompanying drawing, forming part thereof, in which is shown in elevation one of my improved fasteners.

As shown in the drawing, the leading or material feature of my design consists in the upper end horizontal elongated and closed loop *a*, from which depends centrally a deeper and partially-rounded loop portion *b*, the lower contracted end portion of which forms a neck *c*, leading into a smaller terminal loop

d. The width of the central loop *b* is equal to the length of the horizontal or elongated top loop *a*, and the lower terminal loop has imparted thereto a slight vertical elongation.

Having described my invention, what I claim as new, and desire to secure by Letters Patent, is—

The design for a button-engaging attachment for shirt-waists, as herein shown and described.

In testimony whereof I have signed my name to this specification in the presence of two subscribing witnesses.

RICHARD T. CLARKE.

Witnesses:

W. L. MORROW,
A. L. PHELPS.
